UNITED STATES PATENT OFFICE.

PERCY PRESTON, OF DENISON, TEXAS.

REED-BOARD.

1,171,802.

Specification of Letters Patent. Patented Feb. 15, 1916.

Application filed March 19, 1915. Serial No. 15,498.

To all whom it may concern:

Be it known that I, PERCY PRESTON, a citizen of the United States, residing at Denison, in the county of Grayson and State 5 of Texas, have invented a new and useful Reed-Board, of which the following is a specification.

This invention relates to reed organs and is more particularly designed as an improvement on the structure disclosed in my 10 co-pending application filed September 29, 1914, Serial No. 864,104.

One of the objects of the invention is to provide a series of reed cells, the cells of 15 the series being graduated in width and depth and being disposed in pairs, there being a pipe cell in communication with the reed cells of each pair, these pipe cells being of a height gradually increasing in descending the scale.

A further object is to provide ports or 20 openings for maintaining communication between the reed cells and the pipe cells, these ports or holes diminishing in transverse area 25 but increasing in depth in descending the scale and being located at the heels of the reeds.

With the foregoing and other objects in 30 view which will appear as the description proceeds, the invention resides in the combination and arrangement of parts and in the details of construction hereinafter described and claimed, it being understood that 35 changes in the precise embodiment of the invention herein disclosed, can be made within the scope of what is claimed, without departing from the spirit of the invention.

In the accompanying drawings the preferred form of the invention has been shown.

40 In said drawings: Figure 1 is a longitudinal section through one end portion of the structure and showing a plurality of reed cells and pipe cells. Fig. 2 is a plan view of the horizontal partition between the reed 45 cells and pipe cells and showing the ports for maintaining communication between the cells. Fig. 3 is a view of the pipe cells, the same being viewed in the direction of the arrow on line A—B Fig. 1.

50 Referring to the figures by characters of reference 1 designates reed cells of different depths and widths, the depths and widths of the cells increasing in descending the

scale. Each reed cell has a reed block 2 supporting a reed 3.

Arranged longitudinally above the series 55 of reed cells is a series of pipe cells 4 which increase in height and width in descending the scale, one of these pipe cells being provided for every two reed cells and each pipe 60 cell communicating with its reed cells through ports or openings 5. As shown particularly in Fig. 2 these openings diminish in size in descending the scale and also increase in length or depth.

65 It has been found in practice that by graduating the reed cells according to width and depth, by graduating the pipe cells both as to width and height, by graduating the ports or openings 5 as described, the results 70 obtained surpass those heretofore secured because of the better quality of tone and the increase of volume. The reason for varying the width of the cells is that the wider the reed tongue used in cells of equal width, 75 the more direct will be the pull by suction of air through or past the reed and the consequent refusal of the reed to vibrate, it being held down in the strong current or suction. By varying the width of the cells 80 to accommodate the tongues, this trouble is overcome because the air space on either side of the tongue allows the air to pass the reed at right angles as well as up and down.

85 What is claimed is:—

1. In a reed organ, a plurality of reed cells of graduated widths and depths, the widths and depths of the cells increasing in descending the scale, a plurality of pipe cells, said cells increasing in height and 90 width in descending the scale, each pipe cell being in communication with two reed cells.

2. In a reed organ, a plurality of reed cells of graduated widths and depths, the widths and depths of the cells increasing in 95 descending the scale, a plurality of pipe cells, said cells increasing in height and width in descending the scale, each pipe cell being in communication with two reed cells, the openings maintaining communication between the pipe and reed cells gradually decreasing in diameter in descending the scale.

3. In a reed organ, a plurality of reed cells of graduated widths and depths, the widths and depths of the cells increasing in 100 descending the scale, a plurality of pipe cells,

said cells increasing in height and width in descending the scale, each pipe cell being in communication with two reed cells, the openings maintaining communication between the pipe and reed cells gradually decreasing in diameter and depth in descending the scale.

Copies of this patent may be obtained for five cents each, by addressing the "Commissioner of Patents, Washington, D. C."

In testimony that I claim the foregoing as my own, I have hereto affixed my signature in the presence of two witnesses.

PERCY PRESTON.
